UNITED STATES PATENT OFFICE

158,544

SPOON TRAY

Emma Ball, Youngstown, Ohio

Application April 9, 1949, Serial No. 1,889

Term of patent 14 years

(Cl. D44—29)

To all whom it may concern:

Be it known that I, Emma Ball, a citizen of the United States, residing at Youngstown, in the county of Mahoning and State of Ohio, have invented a new, original, and ornamental Design for a Spoon Tray, of which the following is a specification, reference being had to the accompanying drawing, forming a part thereof.

The essential features of my design reside in those portions shown in full lines.

I claim:

The ornamental design for a spoon tray, as shown and described.

EMMA BALL.
